UNITED STATES PATENT OFFICE.

WILLIAM E. ROBERTS, OF BUTTE, MONTANA, ASSIGNOR OF TWO-THIRDS
TO JARED E. GAYLORD AND FRANCIS P. DAVIDSON, OF SAME PLACE.

HEATING AND ROASTING FURNACE.

SPECIFICATION forming part of Letters Patent No. 592,220, dated October 19, 1897.

Application filed May 29, 1897. Serial No. 638,762. (No model.)

To all whom it may concern.

Be it known that I, WILLIAM E. ROBERTS, a citizen of the United States, residing at Butte, in the county of Silver Bow and State of Montana, have invented certain new and useful Improvements in Heating and Roasting Furnaces; and I do hereby declare the following to be a full, clear, and exact description of the invention, such as will enable others skilled in the art to which it appertains to make and use the same.

My invention relates to heating and roasting furnaces, and more particularly to the class of furnaces for calcining, desulfurizing, or chloridizing ores, and is designed as an improvement on the application filed by me December 28, 1895, Serial No. 573,587. Its object is to provide a furnace or roasting-oven, or a series of ovens located one above the other, each provided with a slot or opening extending throughout its side walls between the roof and hearth, whereby the ends of a rake or stirring device adapted to travel over the hearths may project through said slots or openings and pass from one hearth to another, and means for supporting and operating said shaft ends outside of the furnace-walls upon a track supported by brackets which carry the hearths.

It consists in certain details of construction and arrangement of parts, hereinafter more particularly described in the specification, illustrated in the drawings, and pointed out in the claims.

In the accompanying drawings, in which like letters indicate like parts, Figure 1 is a vertical transverse section of my device, showing the hearths, sides, and roofs of the ovens and the brackets by which they are supported and carried and the entire vertical weight sustained. Fig. 2 is a side elevation of same. Fig. 3 is a modification in the form of bracket, showing a block or distance-piece interposed between the brackets. Figs. 4 and 5 are details showing forms of clip or clamp by which the brackets may be secured to the vertical beams which serve as lateral supports or buckstays.

Referring more specifically to the drawings by letter, A represents the arch or roof

of the oven, B the floor or hearth, and C the side walls of the latter.

D is a bracket adapted to carry two longitudinal I-beams E E', which carry and support, respectively, the arch A and the floor 55 or hearth of the furnace and its side walls C.

F represents a series of vertical beams or columns ranged along the sides of the furnace at a short distance from the side walls and against which the outer edge or base of 60 the brackets D bear.

The brackets may be secured to the flanges of the vertical beams by the clips or clamps G, if desired, but this is not essential to enable the brackets to support and carry the 65 hearths, roofs, and side walls of the ovens, and these vertical beams or columns serve merely as braces or buckstays to resist the lateral strain or side thrust of the roofs or arches.

A hearth may be provided beneath the lowermost arch, as shown in the drawings, if desired, and it is obvious that this hearth need not be supported by brackets, as it may be built up directly from the ground.

The foot of the lowermost bracket, which carries the first floor or hearth and its arch, rests upon a substantial foundation built up from the ground, and the foot of the bracket supporting and carrying the roof rests upon 80 and is supported by the former. Therefore the entire vertical weight of the hearths, side walls, and roofs of the respective ovens is carried and supported from the ground by the brackets D, each of which supports and 85 carries the one above, regardless of the vertical beams or columns which merely serve to receive the lateral or side thrust or pressure.

While I have described and shown vertical beams or columns ranged along the sides of 90 the furnace, bearing against the base or back of the brackets to serve as braces or buckstays and take the lateral thrust of the arches, it is obvious that these vertical columns may be entirely dispensed with, and other means 95 that will serve this purpose may be employed. Therefore I do not wish to confine my construction to the use of vertical columns.

H represents tracks resting upon and supported by the brackets D, which tracks sup- 100

port and carry the ends of the rake-shafts which project through the longitudinal openings or slots in the side walls of each oven, and are made to travel over the hearths of 5 the respective ovens by suitable means located outside of the ovens.

While I have shown the base of each bracket resting on the top of the one beneath, it is 10 obvious that this construction may be varied 10 by the use of an interposed block or distance-piece, as shown in Fig. 5, without departing from the spirit of my invention.

I represents a tie-rod at the top of the vertical beams or columns by which they are 15 united on opposite sides of the furnace, and K represents a channel-beam secured to the lower flange of the I-beam supporting the roof-arch and forming a part of the side of the oven.

20 Having thus described my invention, what I claim, and desire to secure by Letters Patent, is—

1. A furnace provided with longitudinal slots or openings extending entirely through 25 its side walls from end to end, a plurality of brackets arranged in vertical series along the sides of the furnace the brackets of each series supported one upon another and carrying and supporting the hearth, roof and side 30 walls, and means for taking the lateral strain of the arches, substantially as and for the purpose described.

2. A furnace provided with longitudinal slots extending throughout its side walls, a 35 plurality of brackets supported one upon another and carrying and supporting the hearth, roof and side walls, means for maintaining said brackets against the lateral thrust of the arches, and a track upon said brackets, adapted 40 to carry and support the ends of a rake-shaft, substantially as and for the purpose set forth.

3. A furnace provided with longitudinal slots throughout its side walls, a plurality of 45 brackets supported one upon another and

carrying and supporting its side walls, hearth and roof, means for maintaining said brackets against the lateral thrust of the arches; tracks upon said brackets, and a rake-shaft passing through said slots in the side walls, 50 and supported upon said tracks, substantially as and for the purpose described.

4. A furnace provided with longitudinal slots through its side walls, a plurality of brackets supported one upon another and 55 from end to end supporting and carrying the hearths, roofs, and side walls, and vertical columns ranged along the sides of the furnace and bearing against the brackets, substantially as and for the purpose set forth. 60

5. A furnace provided with longitudinal slots throughout its side walls, brackets supporting and carrying its hearth, roof, and side walls, each bracket supported by the one beneath, a track upon said brackets, a rake-shaft passing through said slots in the side walls and supported upon said tracks, and vertical columns ranged along the side walls and bearing against said brackets, all arranged substantially as and for the purpose 65 set forth.

6. A series of furnaces or ovens located one above the other, each provided with longitudinal slots throughout its side walls; brackets supporting and carrying their hearths, 70 roofs and side walls, each bracket supported by the one beneath; tracks upon said brackets; a rake-shaft projecting through the slots in the side walls and supported on said tracks; means for operating said rake; and vertical 75 columns or buckstays ranged along the side walls and bearing against said brackets, substantially as and for the purpose set forth.

In testimony whereof I affix my signature in presence of two witnesses.

WILLIAM E. ROBERTS.
